MIDGET VARIABLE RESISTANCE DEVICE

Clarence J. Hathorn, St. Marys, Pa., assignor to
 Stackpole Carbon Company, St. Marys, Pa., a
 corporation of Pennsylvania

Application April 19, 1937, Serial No. 137,653

2 Claims. (Cl. 201—55)

My invention relates to an adjustable resistance device, and relates particularly to an adjustable resistance device employed in radio receiving sets.

Heretofore, it has been customary to have volume controls wherein the external diameter of the housing is larger than eleven-sixteenths of an inch. To reduce the size and the diameter of the adjustable resistance device entails the elimination of parts, which necessarily occupy space within the volume control.

In my present device, the resistance unit may be of a value from 200 ohms to 5 megohms depending upon the use to which the unit is placed; and the unit may serve as a sensitivity control within an automobile radio receiving set, and it also may be used as a tone control. The outside diameter of my new unit is approximately eleven-sixteenths of an inch, and the overall thickness of the unit is approximately one-half inch, which size is considerably smaller than the prior art devices.

Another consideration of the present device is that the shaft should be of substantially the same size as that used in the larger size tone and volume controls, which means that the shaft diameter should be approximately one-quarter of an inch. The bushing on which the shaft is journaled should also be of the type commonly used in the larger size tone of volume controls in order that uniform lock washers may be used to hold the unit in position. Hence, the aforementioned considerations in a small variable resistance unit may be summarized as: a bushing and shaft of normal size, the base, terminals, and resistance element of minute size in comparison to the bushing and shaft.

Since the control is of the potentiometer type, there is a definite or fixed circuit and a derived circuit; hence, three outside electrical terminals should be used.

It is, therefore, an object of my invention to construct a tone control of the adjustable resistance type wherein the same size of the control shaft and bushing as used in the larger type of tone or volume control is used in this midget size unit.

Another object of my invention is to reduce the number of parts in an adjustable resistance unit of the potentiometer type without reducing the corresponding functions.

Another object of my invention is to provide a metallic casing for the adjustable resistance device with an integrally formed fixed outside electrical terminal.

Another object of my invention is to utilize the metallic covering or casing as an electrical conductor of the current from the contact shoe pressure member to one of the derived circuit terminals.

Another object of my invention is to provide an insulating base which may be partially telescoped by the metallic casing and wherein the base and the casing will be held in a predetermined position by complementary holding and positioning means on each of the elements.

Other objects of my invention are to provide an improved device of the character described of simple and economical construction, and which possesses a maximum amount of serviceability and of strength.

With the above and related objects in view, my invention consists of the details of construction and combination of parts that will hereinafter be fully described when the description is read in conjunction with the accompanying drawings in which:

Fig. 1 is a plan view of an adjustable device of the type embodying my invention.

Fig. 2 is a plan view of the rheostat without the casing.

Fig. 3 is a plan view of the base, the terminals attached to the base, and the resistance element.

Fig. 4 is a sectional view taken on the line 4—4 of Fig. 1.

Fig. 5 is an exploded view of the various elements constituting the rheostat.

Fig. 6 is a perspective view of the assembled base and casing illustrating the positioning and holding means on the base and casing.

Fig. 7 is a perspective view of the unit embodying my invention illustrating the position of the outside electrical terminals.

Fig. 8 is a perspective view of the metallic casing.

Referring now in greater detail to the drawings, in Fig. 1 is shown a super midget type of variable resistance device or tone control wherein the overall diameter of the unit is approximately eleven-sixteenths of an inch, and the overall thickness of the unit is approximately one-half of an inch.

A base, generally designated as A, is comprised of insulating material such as Bakelite. The base A of a disc-like arrangement has a central circular bore 10 on which a portion of a rotatable control shaft, generally designated B, revolves.

Integrally molded or formed with the base A is a metallic bushing, generally designated as C,

the latter has external threads 12 thereon for holding the entire unit on a mounting panel (not shown) by means of a lock-nut (not shown), and a central bore 14 of the bushing is in alignment with and is of the same diameter as the base bore 10. In other words, the shaft B is journaled on the bores 10 and 14. A small annular extension 15 integrally formed on the outside of the base A abuts the mounting panel (not shown) to space the electrical conducting elements of the tone control from the mounting panel. The upper surface 16 of the insulator base is substantially flat and ring-like in order to support a ring-like film type resistance element, generally designated as D. The film-type of conductor is preferably of carbon or a mixture of carbon and a binder, and the resistance element has openings 18 and 20 adjacent its ends for the reception of electrical conducting holding rivets or bolts, the latter will hereinafter be further described.

A small peripheral flange 22 adjacent the outer edge of the ring-like surface 16 limits the movement of the resistance element D radially outwardly from the base, and an internal flange 23 concentric with the bore 10 and adjacent the inner edge of the surface 16 limits the movement of the resistance element D in a direction towards the center of the base. Hence, in a small unit 30 of the type now discussed, the small resistance element D is adequately supported so that it will not be shifted out of position, particularly since the combined stop and terminal rivet 24 passes through the complementary opening 18 in the resistance element, a complementary opening 26 in the base, and a complementary opening 28 in an outside terminal 30; and when the outward end of the rivet 24 is peened over, it rigidly holds one end of the resistance element D, the base A, 40 and the terminal 30 together. A flange 32 on the holding rivet 24 abuts against the conducting material of the resistance element D, thus serving to limit the movement of the member 24 in one direction, and from the flange 32 extends a stop portion 33 of the rivet. An electrical conducting rivet or bolt 34 passes through its complementary opening 20 on the resistance element, a complementary opening 36 in the base A, and a complementary opening 38 in one end of another 50 fixed outside terminal 40, and the outside end of the electrical conducting rivet 34 is peened over or expanded to hold the resistance element D, the base A, and the rivet 34 mechanically and electrically together—hence, the value of the resistance between terminals 30 and 40 is fixed.

Upon the outer curved bounding surface 42 of the base A I show four irregularly spaced radially extending prisms, projections, or aligning members 43, 44, 45 and 46. Each of the prisms is 60 similarly constructed, and each side of each prism is approximately one-half of the thickness of the base and serves to position the combined metallic casing and terminal, generally designated as E. The prisms 43 to 46 position the casing E 65 with respect to the base in a direction along the longitudinal axis of the shaft B and in a rotary direction about the longitudinal axis of the shaft. The prisms 44 and 45 on the base are spaced apart so a complementary extension 48 on flange 70 58 of the metallic casing E is positioned between them to align the cover with respect to the base in a predetermined position and in a rotary direction about as well as a rectilinear direction along the longitudinal axis of the shaft. Also, 75 extending from the free end of the casing flange

50 are folding and positioning lugs 54, 57 which cooperate with prisms 46 and 43, respectively. The lug 48 has at its end a folding portion 55, which is adapted to be bent under the base A to prevent the casing and the base from separating; the lug 54 is constructed similarly to and functions the same as the lug 48. Lug 57 is a holding lug adapted to be bent under the base A. Hence, it is to be seen that the casing E partially telescopes the base A to provide a dust-proof housing, and the casing is prevented from totally telescoping the base because of the prisms being engaged by portions of the free edge of the flange 50. If the metallic casing E completely telescoped the base, then the terminals 30 and 40 would be short circuited, since the terminals 30 and 40 are mounted upon the outside surface of the base.

The above described structure is essential in order that fixed terminal 52, which is integrally formed with the casing E, will be closely positioned to the terminals 30 and 40 so that when the tone control is assembled in a radio receiving circuit, the person making the electrical connections to the terminals will have the three terminals 30, 40 and 52 closely aligned together in order to facilitate insertion or soldering of the wire leads to the eyes of the terminals.

The shaft B has a groove 56 therein which receives a split or C washer 58 and the latter 30 abuts against the free end of the bushing C to limit the movement of the shaft in one axial direction.

The end 60 of the shaft B which carries the rotatable insulating control head, generally designated as F, has serrations 62 thereon so that the insulator head F will be securely fastened to the shaft. The rotatable insulator head is molded directly upon the end of the control shaft B so that no additional fastening means need be used 40 to fasten the insulator control head F with the shaft B.

The rotatable insulator head F carries the frictional sliding electrical contact shoe, generally designated as G, and moves the contact shoe G 45 in selective engagement with the resistance element on the longer arcuate distance separating the terminals 30 and 40. The control head F has a flat upper surface 64 and from its lower surface extends an arcuate solid portion 66 which has side surfaces 67 and 68 adapted to engage at different times the stop portion 33 of the rivet 24 in order to limit the rotary movement of the contact shoe G. In other words, when the surface 67 abuts against the stop extension 33 of 55 the stop pin the rotary movement of the insulator head F is limited in one direction, and when the direction of the shaft is reversed until the surface 68 abuts against the pin 24, then the control head is limited in movement in the opposite direction. In other words, the longest circumferential distance between the surface 67, 68 taken on the circumference of the insulator head is the arcuate limitation of rotation of the contact shoe G on the resistance element.

The contact shoe G is comprised of a shaft 70 which longitudinally slides within a complementary opening 72 of the insulator head F and the contact shoe has an expanded contact surface 74 which frictionally slides in engagement with 70 the resistance element D so that the contact surface is kept free of dirt or any corrosive effect. The shaft 70 is greater in length than the thickness 66 of the insulator control head F so that the shoe G may be pressed in engagement by the 75

combined contact shoe pressure member and frictional sliding contact, generally designated as H. The pressure member H is in the shape of an arc of a circle and is mounted on the upper surface 64 of the insulator control head by holding rivets 74, 75 which pass through complementary openings 77, 78. The holding rivet 74 passes through a complementary hole 76 and a complementary opening 77 on the pressure member H and the insulator head F, respectively, and the end of the rivet 74 is expanded to hold the pressure member and control head rigidly together. The rivet 75, constructed similarly to the rivet 74, passes through a complementary opening 78 on the pressure member H and an opening 79 on the control head F and its end is expanded to hold the control head F together with the pressure head.

It is to be observed that the openings 77 and 20 79 in the insulator head F are equally spaced from the opening 72, the latter opening receives the extension 70 of the contact shoe G. Hence, it will be readily seen from an inspection of Fig. 4 that the unsupported portion of the pressure 25 member H presses upon the upper end of the contact shoe G, and there is flexibility of the pressure member H between the unsupported point of contact and the points where the pressure member is supported. The free ends 80 and 81 30 of the pressure and sliding contact H are each constructed to provide a portion of a spherical surface so that the free ends may frictionally engage a disc-like portion 82 of the casing E. Hence, it should be apparent that an electrical 35 connection is established from the resistance element D, through the contact shoe G, the pressure member H, the spherical portions 80, 81, the metallic base 82, the metallic flange 50, and the terminal 52 of the metallic casing E. This 40 construction compared to the prior art devices eliminates at least a fixed or stationary electrical member as well as a fixed terminal fastening member.

A summary of the operation of my invention is 45 as follows:

The impressed or fixed potential difference is between the fixed outside terminals 30 and 40, and the derived circuit or derived voltage may be between the terminal 52 and either terminal 30 50 or 40. When the tone control is in the electrical circuit, the resistance or impedance drop between one end of the resistance element and the contact shoe is varied by rotating the control shaft B, and the control shaft can only be rotated within 55 the limits which is the largest circumferential distance between the control head walls 67 and 68, for either of the walls 67 or 68 may abut against the stop terminal 24 to limit the rotation of the shaft B and consequently the contact shoe. One side of the derived circuit is formed by the 60 current passing along the resistance element D to whatever position contact D may be thereon, and the current flows through the contact shoe G to the pressure member H to the ends 80 and 81 of the pressure member H where the slip ring ends 80, 81 frictionally slide against the disc-like portion 65 of the current collector in the form of casing 80 and around the flange 50 of the casing to the outside terminal 52.

70 Although I have described and illustrated the prisms 43, 44, 45 and 46 as being of one geometri-

cal shape, it is within the scope of my invention to construct the prisms of other geometrical shapes so that the same function may be performed. For example, another geometrical shape is a cylindrical stud whose axis may be extending 5 radially with respect to the longitudinal axis of the control shaft.

Although this invention has been described in considerable detail, such description is intended as illustrative rather than limiting, as the invention 10 may be variously embodied, and the invention is to be determined as claimed.

My invention, therefore, is not restricted except as far as it is made necessary by the prior art and by the spirit of the appended claims. 15

I claim as my invention:

1. An adjustable resistance device comprising an insulating base, a resistance element mounted upon said base, an electric conducting contact shoe for frictionally engaging said resistance element, said contact shoe having a disc-like head in engagement with said resistance element and a cylindrical-like shaft, a rotatably mounted control shaft, an insulating control head having an opening 20 to complementary receive the shaft of the 25 contact shoe, a combined contact shoe pressure member and spring-like electrical contact member, a metallic casing, said combined shoe pressure member engaging the upper end of said contact shoe shaft whereby the contact shoe will be 30 pressed into engagement with the resistance element, and the spring-like electrical contact member being adapted to electrically engage said casing, a peripheral notch on the underside of said insulating control head, a combined rivet holding 35 member and stop member, an outside electrical terminal, said combined member holding one end of the resistance element and the outside terminal to the insulating base, said notch in the insulating head being of an arcuate length equal to 40 the angular movement of the control head, the end walls partially defining the notch on said control head being adapted to abut against the stop member whereby the control will be limited 45 in rotary movement in each direction of movement, an outside terminal integrally formed with said metallic casing, and said casing partially telescoped upon said insulator base.

2. An adjustable resistance device comprising an insulating base, a resistance element mounted 50 thereon, an electric conducting contact shoe for frictionally engaging said element and having a shank terminating in a button-like head, a rotatably mounted control shaft, an insulating control head having an opening therethrough for 55 slidably receiving the shank of the shoe, a metallic casing, a metallic resilient member mounted on said control head and engaging the upper end of the contact shoe shank to bias its button-like head against the resistance element, said resilient 60 member also slidably engaging said casing, an outside electrical terminal, a combined rivet-holding member and stop member holding one end of the resistance element and said terminal to said insulating base and electrically connecting the terminal to the element, said control head being provided with means for engaging said stop member to limit the rotation of the head, and said metallic casing being provided with an 65 outside terminal. 70

CLARENCE J. HATHORN.
